(57) **CLAIM**

The ornamental design for a pot, as shown and described.

DESCRIPTION

FIG. 1 is a top perspective view of a first embodiment of a pot design showing my new design.

FIG. 2 is a bottom perspective view of a first embodiment of a pot.

FIG. 3 is a front view of a first embodiment of a pot.

FIG. 4 is a rear view of a first embodiment of a pot.

FIG. 5 is a left side view of a first embodiment of a pot.

FIG. 6 is a right side view of a first embodiment of a pot.

FIG. 7 is a top view of a first embodiment of a pot.

FIG. 8 is a bottom view of a first embodiment of a pot.

FIG. 9 is a top perspective view of a second embodiment of a pot.

FIG. 10 is a bottom perspective view of a second embodiment of a pot.

FIG. 11 is a front view of a second embodiment of a pot.

FIG. 12 is a rear view of a second embodiment of a pot.

FIG. 13 is a left side view of a second embodiment of a pot.

FIG. 14 is a right side view of a second embodiment of a pot.

FIG. 15 is a top view of a second embodiment of a pot.

FIG. 16 is a bottom view of a second embodiment of a pot.

FIG. 17 is a top perspective view of a third embodiment of a pot.

FIG. 18 is a front view of a third embodiment of a pot.

FIG. 19 is a rear view of a third embodiment of a pot.

FIG. 20 is a left side view of a third embodiment of a pot.

FIG. 21 is a right side view of a third embodiment of a pot.

FIG. 22 is a top view of a third embodiment of a pot; and,

FIG. 23 is a bottom view of a third embodiment of a pot.

Any shading and cross-hatching are not features of the design but are utilized to illustrate the surface contours of the pot design in the drawings.

1 Claim, 23 Drawing Sheets
